UNITED STATES PATENT OFFICE.

JOHN I. MILLETT, OF LOS ANGELES, CALIFORNIA, ASSIGNOR OF THREE-FOURTHS TO
CARL J. IKE, OF LOS ANGELES, CALIFORNIA.

COLLAPSIBLE SUPPORT.

Application filed March 10, 1923. Serial No. 624,166.

To all whom it may concern:

Be it known that I, JOHN I. MILLETT, a citizen of the United States, and a resident of Los Angeles, in the county of Los Angeles and State of California, have invented a certain new and useful Collapsible Support, of which the following is a specification.

This invention relates to collapsible cantilever supports of the kind employed to support tables, chairs, ironing boards and the like.

An object of this invention is to provide a support for a table, chair, ironing board or the like, which is permanently associated with the wall of a building, and which may readily be moved to the open position and readily folded into the collapsed position adjacent a wall of a building where-
20 by in the collapsed position the support does not occupy space in the room.

An object of this invention is to provide an improved cantilever support which is both readily opened and collapsed and in
25 the open position forms a rigid and non-shakable support for a table, chair or ironing board.

Another object of this invention is to provide a cantilever member, one end of
30 which has a sliding engagement with a wall and which is supported by a swinging brace which brace is pivoted at its lower end and provided with a sliding engagement with the cantilever member.

Another object of this invention is to provide a support which is of the disappearing type whereby in a collapsed position the support recedes into a wall.

Another object of this invention is to provide a member which may serve as a chair top, table top or the like, with a collapsible support which support is mounted in a receiving closet formed in a wall whereby the member may serve in the collapsed position
45 as a closure or door for the closet.

Another object of this invention is to provide an arrangement of walls and disappearing collapsible cantilever supports whereby a table and chair arrangement is attained when the supports are moved to the open position.

Various other objects and advantages of this invention will appear from the following description of the accompanying

drawings which illustrate a preferred embodiment of the invention in which—

Figure 1 is a prospective view of a wall and collapsible cantilever support arrangement adapted to form a table and chair arrangement in the open position.

Fig. 2 is a vertical section taken on the line 2—2 of Fig. 1 with the collapsible disappearing cantilever table support moved to the open position.

In the drawings I have illustrated the invention in its preferred embodiment with the supports serving to form either a table top or chair top, which top likewise forms the closure of the support receiving closet 1. The side walls of the support receiving closet 1 are recessed in the form of substantially vertical slideways 2 which terminate at the bottom in forward projecting hooks 3. A cantilever member 5, which serves as the top of a table or chair, is provided with an under rib 4 substantially parallel to the wall, at each end of which is provided a projection 6 engaging one of the slideways 2. While said cantilever member 5 is illustrated as comprising the top of a table or chair, it is obvious said member might serve as the top or support of various other articles.

Said cantilever member 5 is provided with two spaced apart under ribs 8 which extend at right angles from the rib 4 and provide two slideways 9 which extend in the open position outwardly from the wall. 7 indicates a block positioned in the closet 1 to which is pivoted a hinged swinging brace 10, the free end of which brace is provided with cylindrical projections 12 which engage the slideways 9 of the ribs 8. The block 7 extends sufficiently from the rear of the closet 1 so that the brace 10 will be hinged at a point substantially in line with the vertical slideway 2, and the brace 10 is of sufficient length so that when the cantilever member 5 is in the horizontal position with its projections 6 in the forward end 3 of the stationary slideway, the projections 12 of the brace will engage the ends of the slideways 9 and lock the member 5 in position.

The cantilever member 5 is thus provided with a collapsible support of economical and rigid construction. The slideways 2, being formed in opposed side walls of the closet 1, are sufficiently spaced apart so that the member 5 is held from tilting sideways,

to which end the spaced apart position of the under ribs 8, which engage the brace 10, materially aid. The sliding engagement of the brace 10 with the member 5, and the 5 sliding engagement of the member 5 with the wall, permit a ready movement of the cantalever member 5 to the open position. Preferably a recess 13 is provided in the lower wall of the closet 1 so that in the 10 closed position a member 5 may be readily engaged by the hand and pulled outwardly and upwardly to the open position.

Referring to Fig. 1 there is illustrated an 15 arrangement of disappearing collapsible cantalever supports so that when the same are moved to the open position they form a complete chair and table construction. In the Fig. 1, 14 indicates the table top which is supported from a closet 15 in the end wall 20 16. From each side of the end wall extend at right angles two opposed side walls 17, each of which is provided with two closets 18 which receive the supports for the chair tops 19. The opposed walls 17 are spaced a 25 proper distance apart so that upon movement to open position, the table top 14 and chair tops 19 will be in the convenient table and chair arrangement to serve as a breakfast room, card room or the like.

30 This invention is not limited to the particular example described by way of illustration but may be modified in various manners and is of the scope set forth in the following claims.

35 I claim:

1. In a collapsible support, the combination of a cantalever member having projections extending from below its rear end, means forming slideways engaging said projections and permitting the rear of the cantalever member to slide upwardly during a collapsing movement, a brace, and means pivotally mounting the brace, said cantalever member having a groove arranged to 45 engage the brace and support the member on the brace in a horizontal movement and to permit the brace to slide during the collapsing movement of the cantalever member so that such member may completely cover 50 said brace.

2. The combination of a receiving closet

having substantially vertical extending slide-ways in its opposed side walls, a cantalever member comprising a top shape to provide a closure for said closet in one position and having projections extending from below the top into sliding engagement with the opposed slide-ways, said projections being adapted to slide upwardly during the collapsing movement of said cantalever member, a brace, and means pivotally mounting the brace within the closet, said cantalever member having a sliding engagement with said brace.

3. In a collapsible support, the combination of a support receiving closet having substantially vertical extending slide-ways in its opposed sides, a cantalever member adapted to be supported in a horizontal position and mounted so that the rear of the member moves upwardly in permitting the member to assume a vertical position, said member being shaped to provide a closure for said closet while in the vertical position and having projections engaging said slide-ways to guide the rear end of the member during its motion, a brace engaging said cantalever member to support the same in its horizontal position, and means permitting the brace to slide so that the brace is 75 completely covered in the collapsed position by said cantalever member.

4. In a device of the class described, the combination of a support receiving closet having vertically extending slide-ways in 85 its opposed sides, said slide-ways terminating in a forwardly projecting hook at their lower end, a cantalever member shaped to provide a closure for the closet in one position and provided with projections engaging said slide-ways, the slide-ways and projections being arranged so that the rear end of said member slides upward in the collapsing position, and a brace pivoted within the closet and engaging said cantalever member to support the same in a horizontal position and slidably relative to said member in the collapsing motion.

Signed at Los Angeles, California, this 15th day of February, 1923.

JOHN I. MILLETT.
